J. D. PERKINS

LOCK ATTACHMENT FOR DOORS

Filed Feb. 19, 1925

Patented Oct. 27, 1925.

1,558,917

UNITED STATES PATENT OFFICE.

JEFF DAVIS PERKINS, OF JACKSONVILLE, FLORIDA.

LOCK ATTACHMENT FOR DOORS.

Application filed February 19, 1925. Serial No. 10,271.

To all whom it may concern:

Be it known that I, JEFF DAVIS PERKINS, a citizen of the United States, residing at Jacksonville, in the county of Duval and 5 State of Florida, have invented certain new and useful Improvements in a Lock Attachment for Doors, of which the following is a specification.

The present invention appertains to a lock 10 attachment for doors and aims to provide a device which will allow the door to be held ajar and when so held, will prevent persons on the outside thereof from swinging the door to a full open position.

Another important object of the invention 15 is to provide an attachment of this nature which has means incorporated therein whereby the device for holding the door ajar may be actuated from the outside when such is 20 desired.

A further important object of the invention is to provide an attachment of this nature which may be easily installed at a relatively low cost, one which is simple and efficient in construction, reliable in operation, 25 inexpensive to manufacture, strong, durable, and well adapted to the purpose for which it is designed.

With the foregoing and numerous other 30 objects in view as will appear as the description proceeds, the invention resides in certain novel details of construction, and in the combination and arrangements of parts as will be hereinafter more fully described and 35 claimed.

In the drawing

Figure 1 is a sectional view through a door frame showing the attachment holding the door ajar,

Fig. 2 is an enlarged detail end elevation 40 of the bottom portion of the door with portions of the attachment associated therewith, and

Fig. 3 is an enlarged detail section 45 through the door and a portion of the attachment mounted therein.

Referring to the drawing in detail it will be seen that 1 designates a door frame with a door 2 hinged therein in the usual manner. A ratchet plate 3 is embedded in the 50 floor on the inside of the door frame, a slight distance therefrom. A pawl member 4 is pivoted on a bracket 5 at the lower portion of the door on the inside thereof and a chain 6 is attached to the free end of the pawl 4.

A ratchet plate 7 is provided with end arms 8 and 9 which are attached to the inside and outside of the upper portion of the door frame 1 so that the plate 7 extends above the door 2. A ratchet member 10 is 60 fixed to the upper edge of the door for engagement with the plate 7 when the pawl 4 is engaged with the ratchet plate 3 and an effort is made to further open the door, because this will cause the door to raise and 65 engage the ratchet member 10 with the ratchet plate 7, thus positively preventing the door from being fully opened.

A casing 11 is extended through the door 2 and is provided at its outer end with a flange 12 which is adapted to be embedded 70 in a recess provided on the outer surface of the door. The bore of this casing 12 is restricted adjacent its front end so as to provide a shoulder 13. A bolt 14 is slideable 75 through the bore of the casing 11 and is provided at its front end with a knob 15 having an inwardly extending projection 16 adapted to fit or extend in an opening 17 provided in the flange 12. A spring 18 is 80 disposed within the casing 11 above the bolt 14 so that one end impinges against the shoulder 13 and the other end against the knob 15. The inner end of the bolt 14 has 85 an eye 20 which is engaged by the chain 6.

The spring 18 is tensioned so as to exert sufficient pressure against knob 15 so as to slide the bolt through the casing sufficiently to hold the pawl 4 normally out of engagement with the ratchet plate 3. A pair of 90 diametrically opposed openings 21 are provided at the inner end of the casing 11 and an opening 22 is provided at the inner end of the bolt 14 and adapted to be brought into registry with the opening 21 when the projection 16 is fully extended into the opening 17 at which time the pawl 4 is in engagement with the ratchet plate 3 so that pin 24 may be inserted through the openings 21 and 22 for holding the parts in this 95 position and preventing the lifting of the pawl 4 from the outside of the door.

It is thought that the construction and operation of the invention as well as its advantages will now be clearly understood 105 without a more detailed description. It is desired, however, to point out that numerous changes in the details of construction, in the combination and arrangement of parts, may be resorted to without departing from the 110

spirit or scope of the invention as herein-after claimed or sacrificing any of its advantages.

Having thus described my invention, what I claim as new is:—

1. In combination, a door, a pawl pivoted to the bottom portion of the door, a bolt 10 slidable through the door, a chain connected to the bolt and to the free end of the pawl, means for holding the bolt against the movement in the door, and means upon the release of the first mentioned means for normally projecting the bolt from the door so that it may be manually engaged to lift 15 the chain so as to hold the pawl in a non-engaging position and when released will function as a weight for retaining the pawl in said non-engaging position.

2. A device for operating a pawl pivoted 20 to a door including a casing having a bore extended therethrough with a shoulder formed

therein, a flange provided on one end of the casing and having an opening therein, said casing provided with a pair of oppositely disposed openings, an operating bolt adapted 25 to be attached to the pawl and slidable through the casing and provided with a head having a projection adapted to extend into the opening of the flange, said bolt provided with an opening adapted to register with 30 the openings in the casing when the projection of the knob is fully disposed in the operation of the flange, a pin projectable through the openings in the casing and the opening in the bolt, and a spring in the 35 casing impinging against the shoulder and against the knob and held under compression when said pin is projected through the openings in the casing, and the opening in the bolt.

In testimony whereof I affix my signature.

JEFF DAVIS PERKINS.
